UNITED STATES PATENT OFFICE

134,687

DESIGN FOR A TABLE

Chauncey E. Waltman, Chicago, Ill., assignor to Sandel Manufacturing Co., Chicago, Ill., a corporation of Illinois

Application October 3, 1942, Serial No. 108,415

Term of patent 7 years

To all whom it may concern:

Be it known that I, Chauncey E. Waltman, a citizen of the United States and resident of Chicago, in the county of Cook and State of Illinois, have invented a new, original, and ornamental Design for a Table, of which the following is a specification, reference being had to the accompanying drawing, forming a part thereof.

Figure 1 is a view in perspective of the table, showing my new design.

Fig. 2 is a fragmentary sectional view taken along the line 2—2 of Fig. 1 for the purpose of more clearly illustrating the contour of the article.

I claim:

The ornamental design for a table, substantially as shown.

CHAUNCEY E. WALTMAN.
